US00D971325S

(12) United States Design Patent (10) Patent No.: US D971,325 S
(45) Date of Patent: * Nov. 29, 2022

(54) LABEL

(71) Applicant: SmartCreator Co., Ltd., Gyeongsan-si (KR)

(72) Inventor: Bo-Ra Kim, Daegu (KR)

(73) Assignee: SmartCreator Co., Ltd., Gyeongsan-si (KR)

() Term: 15 Years

(21) Appl. No.: 29/797,380

(22) Filed: Jun. 30, 2021

(51) LOC (13) Cl. 19-08

(52) U.S. Cl.

USPC D20/24; D20/27

(58) Field of Classification Search

USPC D20/10, 11, 19, 22, 23, 24, 25, 26, 27,

D20/28, 29, 99

CPC G09F 3/00; G09F 3/10; G09F 3/04; G08B

13/2428; G08B 13/2442

See application file for complete search history.

(57) CLAIM

The ornamental design for a label, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a label showing my new design; and,

FIG. 2 is a rear elevational view thereof.

The broken lines shows boundaries that form no part of the claimed design.

1 Claim, 2 Drawing Sheets
(1 of 2 Drawing Sheet(s) Filed in Color)

FIG. 1

FIG. 2
